GOBLET

William T. Young, Lexington, Ky.

Application October 26, 1953, Serial No. 27,336

Term of patent 14 years

(Cl. D36—8)

To all whom it may concern:

Be it known that I, William T. Young, a citizen of the United States and residing in the city of Lexington, in the county of Fayette and State of Kentucky, have invented a new, original, and ornamental Design for a Goblet, of which the following is the specification, reference being had to the accompanying drawings, forming a part thereof.

In the drawings:

Fig. 1 is a perspective view of a goblet showing my new design.

Fig. 2 is a bottom plan view thereof.

I claim:

The ornamental design for a goblet, substantially as shown.
